Primary Examiner — Brett Miller*Assistant Examiner* — Suzanne E Tisdell(74) *Attorney, Agent, or Firm* — Hanley Flight & Zimmerman LLC(57) **CLAIM**

The ornamental design for a "pen for a printer", as shown and described.

DESCRIPTION

FIG. 1 is a front, right perspective view of a pen for a printer. FIG. 2 is a right side view of the pen for a printer of FIG. 1.

FIG. 3 is a left side view of the pen for a printer of FIG. 1. FIG. 4 is a rear view of the pen for a printer of FIG. 1.

FIG. 5 is a front view of the pen for a printer of FIG. 1. FIG. 6 is a top view of the pen for a printer of FIG. 1; and, FIG. 7 is a bottom view of the pen for a printer of FIG. 1. The broken lines in the drawings illustrating portions of the pen for a printer and surfaces next to the broken lines form no part of the claimed design.

1 Claim, 5 Drawing Sheets(56)
